UNITED STATES PATENT OFFICE.

ALBERT M. CHRISMAN AND JACK E. WELLS, OF PACIFICO, CALIFORNIA.

AUTOMATIC OIL AND GAS SEPARATING PUMP.

Application filed February 16, 1924. Serial No. 693,373.

To all whom it may concern:

Be it known that we, ALBERT M. CHRISMAN and JACK E. WELLS, citizens of the United States, residing at Pacifico, in the 5 county of Kern and State of California, have invented certain new and useful Improvements in Automatic Oil and Gas Separating Pumps, of which the following is a specification.

10 Our invention relates to the class of pumps adapted for use in the production of petroleum.

Our pump is especially applicable in wells where gas is present, in that it is capable of 15 automatically separating the oil and gas, said separation taking place at the point where the oil enters the pump, the gas being mainly excluded, thus relieving the pumping instrumentalities of its presence, 20 and resulting in distinct advantages as will hereinafter appear. In entitling and describing our invention in terms of oil and gas we are simply referring, for the sake of illustration, to the petroleum producing 25 art as the one in which the invention is immediately and particularly applicable. It must be understood however that our pump may be used in any situation and with any fluid-body aggregate comprising 30 a liquid and a gaseous component under circumstances where it will be of benefit to the pump to exclude the gas therefrom. It will also be understood that changes in the form and arrangement and in the 35 details of our pump may be made without departing from the spirit of the invention as defined in the claims hereunto appended. With this understanding we shall now describe our invention in its preferred and 40 practical embodiment, reference being made to the accompanying drawings in which—

Figure 1 is a vertical section of the barrel portion of our pump and its connections; the valve and plunger assembly being omitted.

Fig. 2 is a vertical section, enlarged and broken, of that portion of our pump, which includes the valve and plunger assembly.

Fig. 3 is a vertical section of that portion of the pump in the region in which the separation of the gas takes place, showing the point of entrance of the oil to the annular space within the pump barrel.

Fig. 4 is a vertical section of that portion of the pump in the region in which the oil from the pump barrel enters the in-

terior of the pump to be directed to the plunger and valve assembly.

1 indicates a well and 2 the casing. 3 is the pump barrel which at its upper end 60 is connected with the tubing-string 4 leading to the surface, by the coupling 5, Fig. 3. At the lower end the barrel 3 is connected with the tail-pipe 6, by the coupling 7, the foot of the tail-pipe being closed, 65 Fig. 4.

Within the pump barrel 3 are the liner members 8, usually as here shown, in a plurality of sections. These liners have an exterior diameter sufficiently smaller than the 70 interior diameter of the barrel 3 to leave an intervening space indicated by 9, and said liners are provided with exterior lugs 10 both circumferentially and linearly spaced, which bear against the inner wall 75 of the barrel. The top liner as seen best in Fig. 3, has a collar 11 on its upper end, and the bottom liner as seen in Fig. 4, has a collar 11' on its lower end, said collars closely fitting the barrel thus closing the 80 space 9 above and below, as in Fig. 1. The liners are held in place between the couplings 5 and 7.

The barrel 3 near its upper end has the 85 ports or openings 3', Figs. 1 and 3 through which the well interior communicates with the upper portion of the space 9. The bottom liner has ports or openings 8', Figs. 1 and 4, through which the space 9 at its lower portion communicates with the interior of the pump assembly and with the tail pipe 6. Referring now to Fig. 2, 12 is the upper or traveling-valve assembly, with 90 which is connected the sucker rods 13, above, and the hollow plunger 14 below.

15 is the lower or standing-valve assembly which is seated at 16 in the usual manner in the barrel linings, and has extending 95 downwardly from it the anchor or suction pipe 17. The standing-valve assembly 15 is connected above with the plunger 14 by 100 means of the usual garbutt rod 18 to enable said assembly to be pulled out with the other working parts of the pump.

The operation of the device as indicated 105 by the several arrows, is as follows. The gas and liquid rise together in the well. At the upper ports 3' the separation takes place, the gas passing on up in the well as seen in Fig. 3, while the liquid passes through said 110 ports into the space 9. In this space the liquid descends and passes through the lower

ports 8' as seen in Fig. 4 into the interior of the pump. Thence down in the tail pipe 6 and up through the anchor or suction pipe 17, Fig. 4, the standing valve assembly 15, 5 the plunger 14, the traveling-valve assembly 12, and the tubing string 4 to the surface, Figs. 4, 2 and 3. The separation of the gas from the liquid is due to the downward course which the liquid is compelled initially 10 to take and occurs at the point where the liquid enters the pump structure. The advantage gained is the assured and positive valve action, thus increasing the pumping efficiency.

15 In pumping equipments as usually employed in the production of oil where gas is present, the valve action is not positive, due to the fact that the gas drawn through the bottom valve often collects in the plunger 20 between the valves, thus preventing the pump from obtaining full capacity of displacement, since the gas will not pass out from the pump through the top valve until the pump creates a pressure between the 25 valves sufficient to overcome the weight of the liquid above.

Moreover, the presence of gas also causes valve chatter, which is destructive to the balls and seats of ball-check valves, and 30 oftentimes necessitates the pulling of the pump, to renew said balls and seats. This operation is costly, in addition to wear and tear on equipment, and loss of production. Valve chatter, caused by gas also decreases 35 the efficiency of the pump, due to the fact that the valve does not properly close during pump action.

It will also be seen that by the separation 40 of the gas and oil by means of our pump emulsion is eliminated.

We claim:

1. An oil and gas separating pump comprising a closed barrel adapted for suspension in a well; a liner fitted concentrically 45 within and spaced from said barrel, the space between the barrel and liner being closed above and below, said barrel having ports through which the well communicates

with the upper portion of said space, and said liner having ports through which the 50 lower portion of said space communicates with the interior of the liner; and pumping instrumentalities fitted within said liner intermediate said ports.

2. An oil and gas separating pump comprising a barrel adapted for suspension in a well; a tail pipe carried by the lower end of the barrel, said tail pipe having a closed foot; a liner fitted concentrically within and spaced from said barrel, the space between 60 the barrel and liner being closed above and below, said barrel having ports through which the well communicates with the upper portion of said space, and said liner having ports through which the lower portion 65 of said space communicates with the interior of the liner and with the tail pipe; a hollow plunger operating in said liner intermediate said ports; upper and lower check valves associated with said plunger; and a suction 70 pipe extending from the lower check valve into the tail-pipe.

3. An oil and gas separating pump comprising a barrel adapted for suspension in a well, said barrel having an exterior space 75 with an entrance from the well to its upper portion, and said space having also an entrance from its lower portion into the interior of the barrel; and pumping instrumentalities within the barrel intermediate 80 said entrances.

4. An oil and gas separating pump comprising a barrel adapted for suspension in a well, said barrel having an exterior circumscribing space with closed ends, said 85 space having an entrance in its side to its upper portion from the well, and said space having also an entrance in its side from its lower portion into the interior of the barrel; and pumping instrumentalities within the 90 barrel intermediate said entrances.

In testimony whereof we have signed our names to this specification.

ALBERT M. CHRISMAN.
JACK E. WELLS.
